MARGIN STOP FOR TYPEWRITING MACHINES

Filed Dec. 30, 1932

UNITED STATES PATENT OFFICE

1,969,596

MARGIN STOP FOR TYPEWRITING MACHINES

Bernard J. Dowd, West Hartford, Conn., assignor to Royal Typewriter Company, Inc., New York, N. Y., a corporation of New York

Application December 30, 1932, Serial No. 649,625

7 Claims. (Cl. 197—70)

This invention relates to new and useful improvements in margin stops for typewriters, and embodies certain improvements over the patent to Buckingham 1,053,153, Feb. 18, 1913.

Among the several objects of the invention are to provide a margin stop with means for guiding both ends of the holding latch during relative longitudinal movements between the latch and the margin stop frame whereby the latch will properly cooperate with the teeth of the margin rack on which the stop is mounted; to provide a combined spring and pivot for the latch, and to provide the margin stop with a pointer which extends downwardly for cooperation with a scale located on the front face of the margin rack whereby the margin stop may be located along the rack at any position desired.

With these and other objects in view which will more fully appear, the nature of the invention will be more clearly understood by following the description, the appended claims, and the several views illustrated in the accompanying drawing.

In the drawing:

Figure 1 is a partial plan view of a typewriter carriage showing a margin rack and the right and left margin stops mounted thereon,

Figure 2 is a front elevation of the rack and margin stops, a part of the right hand stop being shown in section,

Figure 3 is a vertical cross sectional view taken on the line 3—3 of Figure 2,

Figure 4 is a similar view taken on the line 4—4 of Figure 2,

Figure 5 is a bottom plan view of the right hand stop showing the same mounted on the margin rack,

Figure 6 is a top plan view thereof,

Figure 7 is an enlarged top plan view of the left hand margin stop showing the same mounted on the margin rack, and

Figure 8 is a view showing in separated perspective the various parts which form the left hand margin stop.

Like reference numerals designate corresponding parts throughout the several figures of the drawing.

Referring to the accompanying drawing, I have shown my improved left hand margin stop X and right hand margin stop Y as being applied to a typewriter carriage which includes end plates 5, 5, the platen 6, and a margin rack 7 which extends between the end plates and on which the margin stops are mounted. This

margin rack 7 includes the usual teeth 8 on its upper surface and a scale 9 on its front surface. A center stop 10 is located in rear of the margin rack 7 and is supported by the main frame of the typewriter in the usual manner.

The left hand margin stop X comprises a rectangular frame a formed of sheet metal and the right hand margin stop Y includes a frame b which is formed from a blank of sheet metal. The frames a and b are slidably mounted on the margin rack 7 for longitudinal adjustments therealong.

The frame a is provided with an interiorly threaded loop 11 for adjustably receiving a stop screw 12 which is adapted to engage the center stop 10 and thereby insure accurate carriage banking, and with a center stop camming lug 13. Slidable on the top of the frame a is a latch c which is also formed of sheet metal and is provided at one end with a fingerpiece 14 and at its other end with a downturned nose 15 for engaging the teeth 8 of the margin rack 7. The latch c is also provided adjacent the nose 15 with guide fingers or lugs 16, 16 which extend downwardly from the side edges of the latch.

The fingers or lugs 16 assist in initially positioning the nose end of the latch laterally with respect to the frame a. The end of the latch c opposite the nose 15 and beyond the fingerpiece 14 is provided with a reduced extension or tail 17. A U-shaped flat spring d is disposed between the frame a and the latch c, one leg 18 of the spring lying flat against the top of the frame a and the other leg 18^a being normally inclined and lying flat against the underface of the latch c.

The legs of the spring normally diverge away from the nose and thereby tend to throw the nose 15 of the latch downwardly into engagement with the teeth 8 of the margin rack. This spring is of sufficient width to be retained against lateral movement by the lugs or fingers 16, 16. The spring is retained against longitudinal movement relative to the frame a and latch c by means of a screw 19 which passes downwardly through a longitudinally extending opening 20 formed in the latch c between the lugs 16, 16 thereof, thence through openings 21, 22 respectively formed in the legs 18, 18^a of the spring d, and thence into a threaded opening 23 formed in the top of the frame a.

It will therefore be observed that the spring constitutes a pivot for the latch, and that the screw 19 also serves to hold the latch and spring in proper cooperative relation on the frame.

Adjustably mounted on the right hand end of

the frame *a* is a cam plate *e* which includes a base 24 having a longitudinally extending opening 25 formed in the left hand end thereof, and with guide lugs or ears 26, 26 which extend 5 downwardly from the sides of the base adjacent the right hand end thereof for engagements with the sides of the frame *a*. Extending upwardly from the right hand end of this cam plate *e* are upwardly extending cam fingers 27, 10 27 which are curved toward the right, that is, away from the opening 25. These cam fingers 27 are spaced apart to receive the tail 17 of the latch *c*. The cam plate *e* is attached to the frame *a* by means of a screw 28 which passes 15 through the elongated opening 25 in the cam plate and into a threaded opening 29 in the top of the frame *a*. When the latch *c* is depressed, the right hand end 17^a thereof will engage the cam fingers 27 and thereby effect a 20 relative longitudinal movement between the latch and the frame *a*. It will, therefore, be seen that the tail 17 has a sliding and interlocking connection with the cam fingers 27, and that by means of this connection together with the 25 screw 19, the latch *c* is guided in a straight line when the same is bodily moved longitudinally relative to the frame *a*. By means of the elongated opening 25 and the screw 28, the cam plate *e* may be adjusted longitudinally on the frame *a* 30 and clamped thereto in any adjusted position. Thus by varying the longitudinal position of the cam plate with respect to the frame *a*, the amount of relative longitudinal movement between the latch *c* and the frame may be correspondingly varied. Thus both ends of the latch *c* are positively guided when the latch is moved longitudinally with respect to the frame *a*, and the spring *d* is retained against swinging movement about the screw 19 by means of the lugs 35 16 which cooperate with the side edges of the legs 18, 18^a of said spring.

Adjustably mounted upon the latch *c* by means of a screw 30 is a pointer *f* which is formed of sheet metal and extends downwardly along the 40 front side of the frame *a* for cooperation with the scale 9 on the front face of the margin rack 7 to locate the margin stop along the margin rack.

In operation, when the latch *c* is raised, the 45 right hand end thereof will engage the cam fingers 27 and cause the frame *a* to move longitudinally towards the right and relative to the latch. The entire stop *X*, with the latch in its raised position, is then moved along the margin rack 7 until the stop screw 12 is in contact with the center stop 10. The latch is then released so that the nose 15 will engage one of the teeth 8 of the margin rack. Thus, the stop screw 12 is set a pre-determined distance away from the 50 center stop, generally one letter space distance, for the reasons well known in the art.

The frame *b* of the right hand margin stop *Y* is identical in construction with the frame *a* of the left hand margin stop *X*, with the exception that the frame *b* is provided at its left hand end with upwardly extending guide fingers 31, 31 which are spaced apart and are integral with the top of said frame. The latch *c*, spring *d*, and pointer *f* are mounted on the frame *b* 55 in the same manner as said parts are mounted on the frame *a*, except that the latch is not mounted for longitudinal movement relative to the frame *b*. Pivotally mounted on the rear wall of the frame *b*, is a bell trip pawl *g* which trips the bell hammer (not shown) when the 60

carriage is moving in one direction and rides over the bell hammer when the carriage moves in the opposite direction.

From the foregoing, it will be observed that the frames *a* and *b* of the margin stops, the latches *c*, the springs *d*, the cam plate *e*, the pointer *f*, and the bell trip pawl *g*, are all formed from sheet metal.

I claim: —

1. In a margin stop for typewriting machines, the combination with a margin stop frame; of a holding latch mounted on the frame for relative longitudinal movements with respect thereto and including a nose and a tail; and cooperating means between the frame and the tail of the latch for guiding and maintaining said latch in a straight line relative to the frame during said longitudinal movements.

2. In a margin stop for typewriting machines, the combination with a margin stop frame; of a holding latch mounted on the frame for relative longitudinal movements with respect thereto; and cooperating means between the frame and latch including guide fingers extending upwardly from the frame at the end thereof opposite the nose of the latch for cooperation with the tail of the latch for guiding and maintaining said latch in a straight line relative to the frame during said longitudinal movements.

3. In a margin stop for typewriting machines, the combination with a margin stop frame; of a holding latch mounted on the frame for relative longitudinal movements with respect thereto, said latch being provided with a tail and with a longitudinal opening adjacent the nose end 110 thereof; a screw passing downwardly through said opening and into the frame; and guide fingers extending upwardly from the frame at the end thereof opposite the nose of the latch for cooperation with the tail of the latch for 115 guiding said latch in a straight line during said movements.

4. In a margin stop for typewriting machines, the combination with a margin stop frame; of a holding latch mounted on the frame for relative longitudinal movements with respect thereto and including a nose and a tail; a U-shaped flat spring disposed between and having its arms engaging the frame and the latch, said arm diverging toward the tail of the latch; 125 said latch adjacent the nose end being provided with a longitudinal opening arranged in register with openings formed in the arms of the spring and in the frame; a screw passing downwardly through said registering openings for retaining 130 the parts against separation; and guide fingers extending upwardly from the frame for cooperation with the tail of the latch for guiding said latch in a straight line during the longitudinal movements thereof relative to the frame.

5. In a margin stop for typewriting machines, the combination with a margin stop frame; of a holding latch mounted on the frame for relative longitudinal movements with respect thereto and including a nose and a tail; a U-shaped flat spring disposed between and having its arms engaging the frame and the latch, said arm diverging toward the tail of the latch; said latch adjacent the nose end being provided with a longitudinal opening arranged in register with 140 openings formed in the arms of the spring and in the frame; a screw passing downwardly through said registering openings for retaining the parts against separation; ears depending from the sides of the latch for embracing the 145

spring to retain the latter in operative position; and guide fingers extending upwardly from the frame for cooperation with the tail of the latch for guiding said latch in a straight line during the longitudinal movements thereof relative to the frame.

6. In a margin stop for typewriting machines, the combination with a margin stop frame; of a holding latch mounted on the frame for relative longitudinal movements with respect thereto, said latch being provided with a nose and a tail and with a longitudinal opening adjacent the nose; a spring disposed between the latch and frame and normally urging the nose of the latch downwardly toward the frame; a screw passing downwardly through said opening and into the frame; and a cam plate mounted on the end of the frame adjacent the tail of the latch for longitudinal adjustments along said frame, said cam plate having spaced guide fingers extending upwardly and in a direction

away from the nose of the latch for cooperation with the tail of the latch for guiding said latch in a straight line during longitudinal movements thereof and for cooperation with the adjacent end of the latch for effecting a longitudinal movement of the latch in a direction away from said fingers when said latch is depressed to elevate the nose thereof.

7. In a margin stop for typewriting machines, the combination with a margin stop frame; of a holding latch mounted on the frame and including a holding nose and a tail; a U-shaped spring disposed between the latch and the frame and constituting a pivot for the latch and serving normally to elevate the tail of the latch; and a limiting element extending downwardly through the latch and the spring and engaged in the frame; said frame, latch and spring being all formed of sheet metal.
